UNITED STATES PATENT OFFICE.

IRVIN C. HUFFMAN, OF DUBLIN, GEORGIA, ASSIGNOR OF ONE-HALF TO
J. S. HUFFMAN, OF DUBLIN, GEORGIA.

LIFTING-JACK.

No. 817,017.

Specification of Letters Patent.

Patented April 17, 1906.

Application filed October 30, 1905. Serial No. 285,215.

To all whom it may concern:

Be it known that I, IRVIN C. HUFFMAN, a citizen of the United States, residing at Dublin, in the county of Laurens and State of Georgia, have invented certain new and useful improvements in Lifting-Jacks; and I do declare the following to be a full, clear, and exact description of the invention, such as will enable others skilled in the art to which it appertains to make and use the same.

My invention relates to lifting-jacks of the screw type, and more particularly to a ball-bearing head or cap for the same.

One object of the invention is to provide a simple and efficient construction which may be applied to either old or new jacks, so as to provide a ball-bearing or antifriction head or cap upon the same.

A further object of the invention is to improve and simplify the construction and operation of devices of this character, and thereby render the same more efficient and durable in use and less expensive to manufacture.

With the above and other objects in view the invention consists of certain novel features of construction, combination, and arrangement of parts, as will be hereinafter more fully described and claimed.

In the accompanying drawings, Figure 1 is a vertical sectional view through a screw-jack with my improved ball-bearing head or cap applied thereto. Fig. 2 is a top plan view of the same. Fig. 3 is a horizontal sectional view taken on the line 3-3 in Fig. 1, and Fig. 4 is a detail vertical sectional view through a slightly-modified form of the invention.

Referring to the drawings by numeral, 1 denotes the screw of a jack, which has its lower end working in the threaded opening in a suitable base 2, which, as shown, is provided with a hand-grip 3. At the upper end of the screw 1 is a cylindrical enlargement 4, which is formed at its top with a concentrically-disposed upwardly-projecting reduced stem or projection 5. The latter is adapted to receive a rotatable head or cap 6, which is in the form of an annular plate or ring, through the central opening in which said stem 5 projects. This head or cap 6 is supported upon antifriction-balls 7, which are arranged in an annular row around the stem

5 and between the under side of the head or cap and the upper side of the enlargement 4 of the screw. Washers 8 9 are preferably interposed between the balls and said parts, and said balls are retained in position by a ring 10 and a sleeve 11. The ring 10 surrounds the stem 5, and the sleeve 11 is screwed or otherwise secured, as at 12, upon the upper portion of the enlargement 4. This sleeve terminates slightly beneath the top or upper face of the head or cap 6. The latter is preferably retained in position by a set-screw 13, which engages a threaded opening in the top of the stem 5 and has its head countersunk in a recess 14, formed in the top of the head or cap 6. Suitable openings 15 are provided in the enlargement 4 to receive a removable lever 16, by means of which the jack is operated, as will be readily understood.

It will be seen that the foregoing construction may be applied to any screw-jack, so as to provide a ball-bearing head or cap upon the same, or it may be applied to a new jack when it is manufactured; but when the ball-bearing head or cap is applied to the jack when it is manufactured I preferably employ the construction shown in Fig. 4 of the drawings. In this construction it will be seen that the washers 8 9, the ring 10, and the sleeve 11 are omitted, and the bearing-balls are seated in annular grooves 17, formed in the opposing faces of the head or cap and the enlargement. The head or cap is retained in position by heading the upper end of the stem or projection 5, as shown at 18.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

A device of the character described comprising a jack-screw having at one end a cylindrical enlargement and a reduced cylindrical stem, a head or cap upon said stem and formed in its top with a circular recess, a

set-screw in said stem and having its head seated in said recess, bearing-balls arranged around said stem between said cap and said enlargement, washers interposed between 5 said bearing-balls and said cap and enlargement, a ring surrounding said stem and arranged within the row of bearing-balls, and a sleeve carried by said enlargement and adapted to retain said bearing-balls between said

cap and enlargement, substantially as described.

In testimony whereof I have hereunto set my hand in presence of two subscribing witnesses.

IRVIN C. HUFFMAN.
